HENRY G. LYKKEN, OF MINNEAPOLIS, MINNESOTA

FUEL-BURNING DEVICE

Application filed September 11, 1928. Serial No. 124,792.

The present invention relates to the burning of fuel, such as coal.

Among the objects of the invention is to provide a novel fuel burning device, such as for locomotive boilers, particularly for the burning of pulverized or powdered fuel, such as pulverized coal and the like. Attempts at using a powdered fuel in locomotives, having fire tubes ahead of the fire box, have been 10 unsuccessful for several reasons, such as the inadequacy of the combustion space or spaces for the powdered fuel to attain complete or proper combustion, correct draft effects on the firebed in the firebox, and the design of a 15 locomotive for usual firing being improper for powdered fuel.

The present invention, therefore comprehends the provision of a series of combustion spaces or chambers, preferably of large 20 capacity, wherein efficient combustion of powdered fuel may be effected. In a specific embodiment this may be attained by providing a large combustion chamber ahead of the firebox so as to act as a secondary combustion 25 chamber and the firebox space may act as a primary combustion chamber. The secondary combustion chamber may also act as a large flue. Preferably, this chamber has corrugated walls for giving added heating surface 30 and for facilitating the differential expansion and contraction thereof. It may also have means for supporting it whereby it may slide when expanding or contracting. Specifically, the support may comprise supporting 35 members located in the water and steam containing space around the corrugated chamber, and be secured to the outer shell, and have ledges or supporting surfaces upon which may rest or be supported, supporting elements rigid with the chamber. Differential 40 expansion of the outer shell and this chamber may be compensated by the supporting members and elements relatively sliding.

Another object of the invention is to provide means for maintaining an incandescent firebed, such as a bed of fuel upon a grate, and directing one or more streams of powdered fuel, preferably mixed with a supporter of combustion, such as air, toward the firebed as 45 downwardly toward the same. Means may

also be provided, preferably, for controlling and regulating the mixture, both as to the total quantity supplied to the chamber of the firebox and also as to the relative proportions of the powdered fuel and the air. The 55 firebed may act as a means for igniting the projected mixture and also to maintain the same ignited. Means are also provided for supplying air to the firebed or for cutting off the air entirely, dependent upon the load to 60 be carried by the locomotive. When operating at a high rate or under a heavy load, the heat transfer is preferably practically all effected from combustion of powdered fuel and air, in the primary and secondary chambers, but when the locomotive is at a low load, coasting or the like, the powdered fuel may be accordingly reduced, or cut off and the heat from the firebed used only, air being admitted in the desired amount for such 70 effect. Should the powdered fuel device cease to operate for any reason, as by reason of damage occasioned thereto, the firebed may be operated in the usual manner for operating the locomotive under reduced power or load. 75 Desired heat effect may also be had by a combined combustion of the powdered fuel and of the fuel on the firebed with the required amount of air for supporting combustion of the latter. 80

Another object of the invention is to effect the heat transfer mainly by radiation. Combustion of the powdered mixture is preferably initiated and partly effected in the primary chamber and substantially completed 85 in the secondary chamber, volatiles in the fuel distilling off in the heat of the primary chamber with the products of distillation breaking up so that the larger part of the volatiles are burned in the primary chamber. Nearly all of the carbon will burn to carbon monoxide there. The higher heat in the relatively larger secondary chamber or flue, and the sufficient supply of air or oxygen supplied 90 will effect a complete combustion therein, so that the carbon monoxide is burned to carbon dioxide, and the combustion completed therein. The greater part of the heat produced in these chambers will be absorbed or trans- 100

ferrered through the wall of the secondary chamber.

The invention may or may not include as a feature, a waste heat absorber or economizer, preferably located at the discharge end of the secondary chamber. No means for inducing a draft is necessary and hence the back pressure on the engine heretofore found necessary, is wholly eliminated in this invention, thus adding to the efficiency of the plant. The pressure of the fluidal mixture at the blowers for projecting the powdered fuel through the burner is low but sufficient to effect a flow of the products of combustion through the heat absorber, and for the removal of the gases from the stack.

By utilizing large volume combustion chambers, the passage of the material, gases and flames therein, is without substantial resistance and is much freer than through a multiple of fire tubes heretofore used and requiring high induced draft. Progressive burning in the chambers is effected with a completion of combustion in the secondary chamber, and hence a maximum transfer of heat.

In this invention the ash pit is entirely closed or sealed air tight with the exception of a control door for admitting air into the ash pit and beneath the grate holding the incandescent fire bed. The control door may be entirely closed or held in adjusted position for regulating the amount of air to be admitted to the fire bed.

The terms "incandescent" or "incandescence" used herein are used in the sense of low degrees of incandescence or glowing as well as of higher degrees thereof.

Other objects, advantages, capabilities and features are comprehended by the invention as will later appear and are inherently possessed thereby.

Referring to the drawings,

Fig. 1 is a longitudinal sectional view through a locomotive boiler constructed in accordance with the invention;

Fig. 2 is a fragmentary top plan view of a rear portion thereof showing parts in broken section; and

Fig. 3 is a transverse sectional view of the boiler.

Referring now more in detail to the drawings, the embodiment selected to illustrate the invention is shown as comprising an outer shell 1 having a space 2 therein for the containing of water and steam. At the rear end of the chamber is located a fire box or primary combustion chamber 3 in the lower part of which is provided a grate 4 located above a closed ash pit 5. The ash pit may have one or more air admitting openings 6 controlled by adjustable closures 7 cooperating with a sector 8 or the like whereby the closure 7 may be held at any desired adjusted open position. Upon the grate 4 may also be located a fire bed

9 of incandescent fuel. This fuel may be supplied to the bed in the usual way thru a firing or stoking opening 10 normally closed by a fire door 11. The ash pit 5 is normally closed and sealed from entry of outside air except through the opening 6 as controlled by the door 7.

Leading from the discharge end 12 of the primary chamber 3 is a corrugated secondary chamber 13 extending for a substantial length throughout the locomotive toward the forward end thereof. This chamber 13 is of large capacity and serves both the purpose of a combustion chamber as well as a flue for the passage of the hot gases therethrough.

For the purpose of supporting this second chamber whereby it and shell 1 may contract or expand, or in other words, whereby both may differentially expand and contract, a supporting means is provided comprising supporting members or ledges 14 secured to side portions of the outer shell 1 as by way of rivets or the like 15 and 16. The members 14 have supporting surface portions 17 which are substantially in horizontal planes and upon which rest angular elements 18 secured to the sides of the chamber 13 as by rivets or the like 19. It will also be noted that the width of the surfaces 17 is greater than that of the member 18 so that relative movement of the two may be had for a substantial degree. In this way the chamber 13 is supported upon the members 14 so that if the chamber 13 should expand or contract the members 18 will be adapted to have a sliding movement over the surfaces 17, depending upon the direction of expansion or contraction. On the other hand should the chamber 1 be expanding or contracting, the members 14 will slide under the members or elements 18 in the same way. This of course, affords, a simple and facile means for taking care of differential contraction and expansion as regards the chamber 13 and the shell 1.

At the forward end of the chamber 13 may be provided a heat absorber comprising a group of vertical water tubes 20 communicating at the upper and lower ends thereof with the space 2 in the shell 1 and among which may pass the products of combustion from the chamber 17 to the discharge or outlet stack 21. If desired a plate 22 may be used to control the flow of the hot gases among the tubes 20. In this way whatever waste heat may remain in the gases passing from the chamber 13, will be absorbed in the tubes 20 to preheat the water at the forward end of the locomotive.

The locomotive may be provided with other features, pertaining thereto, such as the steam take off 23 having connection to the engines and a steam dome 24 as is usual.

At the rear end of the locomotive, the fire pot 3 is made of large capacity, and has connected thereto at the upper part thereof, one

or more burners or nozzles, 25 for discharging powdered or pulverized fuel and air downwardly into the chamber 3 and toward the fire bed 9. Each nozzle 25 is connected to a discharge duct 26 having a control valve 27 and leading from a blower or fan 28 having an inlet 29. The fan may also have one or more openings 30 controlled by shutter 31 of any desired construction, whereby additional air may be admitted into the fan to be mixed with the powdered fuel or the same with the air mixed therein supplied to the fan.

In the operation of the device, a fire bed 9 is built and maintained upon the grate in incandescent state. The ash pit may be entirely closed or partially opened by adjusting the door 7. One or more controlled and regulated streams of pulverized fuel with the air, is then projected from one or more burners 25 downwardly into the space of the primary chamber 3 and toward the fire bed 9. The latter will act to ignite and maintain in ignited condition the combustible mixture. The gate 27 may be of utility to control the total amount of the mixture so projected. If it be desired to vary the richness or leanness of the mixture, the shutter 31 may be closed or open to vary the amount of air that may be introduced through the opening 30 for mixing with the mixture passing through the blower to the burners.

Combustion first takes place in the chamber 3 so that the volatiles in the coal may be distilled off in the heat in this primary combustion chamber and the products of combustion break up so that most of the volatiles will burn. Practically all of the carbon will burn to carbon monoxide and a small part of it to carbon dioxide. As the burning mass passes into the secondary chamber 13 the combustion is completed therein. The heat therein is of a higher degree so that the carbon monoxide will burn to carbon dioxide, it being assumed that sufficient air was originally admitted with the pulverized material to make a complete combustion in the secondary chamber. The proper amount of air is controlled by the amount mixed with the pulverized fuel and the amount permitted to be introduced through the opening 30. Also, where air is being admitted to the fire bed, a part of the same may also be included.

In this way, a large volume of fire may be maintained for high duty work. It may also be varied in accordance with the load being imposed upon the locomotive. When, however, the locomotive is in a substantially idle condition, such as coasting down a grade, or stopped at a station, the pulverized fuel may be reduced or entirely shut off and pressure in the boiler may be maintained only from the fire in the fire bed 9. More air may be admitted through the opening 6 to make this fire bed burn to the desired amount to

70 maintain the boiler and reduce load condition. On the other hand, should the pulverized fuel feature not operate, the boiler may be fired by causing the fuel in the fire bed to burn in the usual manner with a natural draft of air from the opening 6 so that the locomotive may proceed under reduced load.

75 It will be noted that practically all the fuel burned may be that of the pulverized form by shutting off all of the air under the grate, the fire bed only then acting as a means of igniting and maintaining in ignition the pulverized combustible mixture. The bed on the grate may be maintained at such a thickness as to protect the grate from the heat in the furnace. When little or no air is admitted through the grate, the material on the grate will remain incandescent, but will burn slowly and requiring very little replenishment. When the load drops off the boiler, 80 the pulverized coal feed may then be shut off or reduced to the desired point.

85 After completion of combustion in chamber 13, the remaining hot gases of combustion may pass through the absorber to give up 90 waste heat to the water and steam at the forward end of the locomotive, after which the gases may pass freely upwardly through the stack 21. No induced draft is necessary in this construction, thus eliminating the disadvantage of the back pressure heretofore necessary in locomotives to produce drafts. The mixture of pulverized fuel and air is supplied to the fire box or primary combustion chamber under a low pressure sufficient to cause a 95 flow of the gases, while they are burning through the chambers, and finally through the absorber and out through the stack. The rate of flow of these gases may be controlled by varying the speed of the blowers. While 100 the gases are passing through the chambers, the larger part of the heat absorbed thereby or transmitted thereto is by radiation, a small portion only being absorbed or transmitted by connection through the fire box and flue 105 shell or secondary chamber.

110 While I have herein described and upon the drawings shown an embodiment of the invention, it is to be understood that the same is not limited thereto but may comprehend 115 other constructions, arrangements, details, features and other steps of the process, without departing from the spirit thereof.

Having thus disclosed the invention, I claim:—

120 1. A locomotive fuel burning device comprising a combustion chamber at one end and a stack at the other end, said combustion chamber having a fuel introducing opening in the rear wall thereof, means for normally maintaining a fuel bed in the bottom of said chamber, an elongated tubular extension of approximately uniform diameter leading from the front end of said combustion chamber, and above the normal level of the fuel 125 130

bed approximately to said stack, and means for forcibly projecting a mixture of powdered fuel and air into said combustion chamber above said fuel bed so that said mixture will be initially ignited by the fuel bed and its combustion will be completed within said tubular extension.

2. A locomotive fuel burning device comprising a combustion chamber at one end and a stack at the other end, said combustion chamber having a fuel introducing opening, means for normally maintaining a fuel bed in the bottom of said chamber, an elongated tubular extension of approximately uniform diameter leading from the front end of said combustion chamber to said stack from a position above the normal plane of said fuel bed, said combustion chamber and said extension having walls provided with heat transferring surfaces, means for controlling the air supplied to said fuel bed, means for forcibly projecting a mixture of powdered fuel and air into said primary combustion chamber above said fuel bed so that the mixture will be initially ignited by said fuel bed and its combustion will be completed within said tubular extension, and means for varying the proportions of air and powdered fuel.

3. A locomotive fuel burning device comprising a combustion chamber at one end and a stack at the other end, said combustion chamber having a fuel introducing opening, means for normally maintaining a fuel bed in the bottom of said chamber, an elongated tubular extension of approximately uniform diameter leading from the front end of said combustion chamber to said stack from a position above the normal plane of said fuel bed, said combustion chamber and said extension having walls provided with heat transferring surfaces, means for controlling the air supplied to said fuel bed, downwardly projected feed pipes connected with the top of said combustion chamber and communicating with the interior of said chamber, and means for forcing a mixture of powdered fuel and air through said feed pipes downwardly into the combustion chamber over said fuel bed so that said mixture will be initially ignited by said fuel bed and its combustion will be completed within said tubular extension.

4. A locomotive fuel burning device comprising a combustion chamber at one end and a stack at the other end, said combustion chamber having a fuel introducing opening, means for normally maintaining a fuel bed in the bottom of said chamber, an elongated tubular extension of approximately uniform diameter leading from the front end of said combustion chamber and above the normal level of the fuel bed approximately to said stack, the wall of said extension being corrugated, means supporting said extension at

positions intermediate between its ends, said extension and said supporting means having complementary surfaces upon which the extension is free to expand and contract in any direction, and means for forcibly projecting a mixture of powdered fuel and air into the combustion chamber above said fuel bed so that said mixture will be initially ignited by the fuel bed and its combustion will be completed within said tubular extension.

5. A locomotive fuel burning device comprising a combustion chamber at one end and a stack at the other end, said combustion chamber having a fuel introducing opening in the rear wall thereof, means for normally maintaining a fuel bed in the bottom of said chamber, an elongated tubular extension of approximately uniform diameter leading from the front end of said combustion chamber and above the normal level of the fuel bed approximately to said stack, means for forcibly projecting a mixture of powdered fuel and air into said combustion chamber above said fuel bed so that said mixture will be initially ignited by the fuel bed and its combustion will be completed within said tubular extension, means providing supporting surfaces, and support members carried by said tubular extension and resting freely upon said supporting surfaces so as to move in any direction in accordance with the movements due to expansion and contraction of said tubular member.

In witness whereof, I hereunto subscribe my name to this specification.

HENRY G. LYKKEN.
